TOY SHEEP

Bill Markham, Los Angeles, Calif., assignor to Lakeside Industries, Inc., Minneapolis, Minn., a corporation of Delaware

Filed Oct. 17, 1962, Ser. No. 72,153

Term of patent 14 years

(Cl. D34—2)

FIG. 2

FIG. 1

FIG. 4

FIG. 1 is a side elevational view of a toy sheep embodying my new design;

FIG. 2 is a top plan view thereof;

FIG. 3 is a front elevational view thereof; and

FIG. 4 is a rear elevational view thereof.

I claim:

The ornamental design for a toy sheep, as shown.
